CLAIM

The ornamental design for an eyeglasses temple with star temple tip, as shown and described.

DESCRIPTION

FIG. 1 is a perspective view of my new design showing an eyeglasses temple with star temple tip;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is another perspective view of my new design showing an eyeglasses temple with star temple tip.

The broken lines shown in the drawings are for the purpose of illustrating environment and form no part of the claimed design.

1 Claim, 2 Drawing Sheets
